STARTER

Filed May 9, 1927

UNITED STATES PATENT OFFICE

WILLIAM CARLETON STARKEY, OF INDIANAPOLIS, INDIANA, ASSIGNOR TO L. G. S. DEVICES CORPORATION, OF INDIANAPOLIS, INDIANA, A CORPORATION OF INDIANA

STARTER

Application filed May 9, 1927. Serial No. 190,030.

It is the object of my invention to produce a starter drive particularly adaptable for use in connection with automobile engines, which starter drive will embody but few 5 parts, will be capable of construction at a low cost, and will be effective in operation.

I accomplish the above object by mounting on the shaft of the starter motor a slideable pinion gear which meshes with a gear rotatable with the engine crank shaft, both gears being preferably helical, and I connect the pinion to the starter motor shaft through an overrunning clutch which is slideable as a unit with the pinion along the starter motor 15 shaft to carry such pinion into and out of engagement with its associated gear. I provide means operated jointly with the starter motor switch for moving the pinion into engagement with its associated gear, and in this 20 pinion moving mechanism I incorporate a latch which will permit disengagement of the pinion and gearing even though the starter-motor switch is closed.

The accompanying drawing illustrates my 25 invention: Fig. 1 is a longitudinal section of my device showing the parts in the positions which they occupy when the starter motor is not in operation; Fig. 2 is a fragmental longitudinal section similar to Fig. 1 but with the parts in the positions they occupy when the starter motor is rotating the engine; and Fig. 3 is a fragmental longitudinal section 29 through a device embodying a modification of my invention.

Rotatable with the engine crank shaft and preferably secured to the fly wheel 10 of the engine is a helical gear 11. A starter motor (not shown) is mounted beside the engine with its shaft 12 parallel to the axis of rotation of the gear 11 and with the rear end of such shaft projecting past the plane of the gear. My invention is not concerned with details of the starter motor or its mounting.

The starter motor is supplied with current from a battery 14 through an electrical conductor 15 in which is incorporated a suitable switch 16. The switch 16 may be of any desired type, the one shown comprising two contacts 17 and 18 which are insulated from each other and which are adapted to be con-

nected by a brush 19. The brush 19 is vertically movable with a button 20 adapted to be moved downward by the foot of the operator to bring the brush into engagement with the contacts 17 and 18. My invention is 55 not concerned with the details of this switch construction.

Slidably mounted on the rear end of the shaft 12 but rotatable therewith is a cup-shaped clutch member 22. To form a suitable mounting for this clutch member on the shaft 12, it is conveniently provided with a hole for receiving the end of the shaft 12, such hole having splines which co-operate with splines 23 on the end of the shaft. The 60 clutch member 22 is counterbored to receive a second clutch member 24 which is also cup-shaped. The clutch member 22 extends forwardly beyond the bottom of the cup 24 and is there provided in its inner surface with an 65 annular groove for the reception of a split spring ring 25 which prevents axial separation of the two clutch members. Rigid with the clutch member 24 is a helical pinion 27 which moves into and out of engagement 70 with the gear 11 as the clutch members 22 and 24 are moved axially along the shaft 12.

Located within the clutch members 22 and 23 is a helical coil spring 28 which, in the arrangement shown, is of the same hand 80 as the helical pinion 27. This spring 28 has a normal external diameter slightly greater than the internal diameter of the recesses in which it is received; so that when it is in 85 place in such recesses, it presses outwardly against the walls thereof.

The clutch formed by the clutch members 22 and 24 is conveniently enclosed within a clutch casing 30 which is conveniently mounted on the end wall 31 of the casing 90 which surrounds the starter motor and its shaft 12. Slidably mounted in the end wall of the casing 30 is a thrust member 32 the forward end of which bears against the rear face of the clutch member 22. If necessary, the front face of the thrust member 32 may be provided with an axial recess 33 for the purpose of providing clearance for the end of the shaft 12.

The thrust member 32 is designed to be 100

5 moved forwardly when the starter motor switch is closed, such forward movement bringing the pinion 27 partially into mesh with the gear 11. To accomplish this result, the thrust member 32 is connected to a longitudinally extending rod 35 which is connected through a compression spring 36 with one arm of a bell crank 37. The other arm of the bell crank 37 is engaged by a member 38 which is movable with the brush 19 of the 10 starter-motor switch. A spring 40 acts between the rod 35 and any fixed point tending to force the rod rearwardly to hold the bell crank 37 in engagement with the member 38.

15 In the construction just described, pressure on the switch button 20 lowers the member 38, and causes the bell crank 37 to move the rod 35 forwardly. This movement of the rod 35 is transmitted through the thrust member 32 to the clutch member 22 which, with the other clutch member 24 and pinion 27, is moved forwardly far enough to bring the pinion 27 into partial engagement with the gear 11. Downward movement of the 20 switch button 20, after engaging the pinion 27 with the gear 11, brings the brush 19 into engagement with the contacts 17 and 18 thus closing the starter-motor circuit. The resultant rotation of the starter-motor shaft 30 12 is transmitted through the overrunning clutch to the pinion 27 and causes such pinion to tend to rotate the gear 11. The reaction of the teeth of the gear 11 on the inclined teeth of the pinion 27 causes the pinion to move still farther forward until it reaches complete engagement with the gear 11 when its forward face abuts against a suitable stop 42. Further rotation of the shaft 12 causes rotation of the gear 11 to 25 start the engine.

30 When the engine begins to run under its own power, it tends to drive the pinion 27, and the reactions at the faces of the teeth of the gear 11 and pinion 27 are reversed tending to cause rearward movement of the pinion 27, thus carrying the pinion axially out of engagement with the gear 11.

35 To permit such rearward movement of the pinion 27 even although the button 20 of the starter-motor switch is still depressed, the rod 35 is not directly connected to the thrust member 32. Instead, the thrust member 32 carries a pivotally mounted latch 50 which is adapted to swing transversely into and out of engagement with the end of the rod 35. A coil spring 51 acting between the thrust member 32 and a lateral projection 52 on the latch 50 tends to hold the latch in engagement with the end of the rod 35. Such engagement exists when the parts are in the 40 position shown in Fig. 1 and the starter-motor is not in operation. When, however, the switch button 20 is depressed sufficiently to bring the brush 19 into engagement with

the contacts 17 and 18, forward movement of the thrust member 32 brings the latch-extension 52 into engagement with an abutment, conveniently the end of the housing 30, which serves to move the latch 50 out of engagement with the end of the rod 35. The position of the parts while the starter-motor is cranking the engine and while the switch button 20 is still depressed is shown in Fig. 2. If, now, the engine begins to run under its own power, the reaction of the gears 11 and 27 tends to move the pinion 27 and clutch members 24 and 22 rearwardly to carry the pinion out of engagement with the gear 11. Since the latch 50 is out of engagement with the end of the rod 35, this movement is permitted even though the rod 35 is in its forward position. Subsequent release of the switch button 20 permits the rod 35 to move rearwardly under the action of the spring 40, and the latch 50 then returns to a position where it will be engaged by the front end of the rod 35.

45 I have found it advisable to provide some means for preventing accidental axial displacement of the overrunning clutch and pinion 27. To this end, I provide axially spaced peripheral grooves 55 in the outer face of the clutch member 22, and I provide a spring 56 the end of which is adapted to enter one or the other of the grooves 55 to hold the clutch and pinion either in engagement with the gear 11 or out of engagement with such gear.

50 In the construction as so far described, the teeth of the pinion 27 may meet those of the gear 11 in such a position as to prevent further forward movement of the pinion 27 until after it has been rotated slightly. When such engagement of the gear and pinion teeth occurs, the spring 36 is compressed and permits complete depression of the switch button 20 to close the starter-motor circuit. The resultant rotation of the starter-motor shaft 12 changes the relative positions of the teeth of the gear 11 and pinion 27, thus permitting the pinion 27 to move into meshing engagement with the gear. It sometimes happens, however, that the starter motor starts very suddenly with the result that the pinion teeth do not immediately drop into the spaces between the teeth of the gear 11. To avoid this, I may employ the construction illustrated in Fig. 3, which is so arranged that meshing engagement of the pinion 27 and gear 11 will occur before the starter-motor circuit is closed.

55 As has been pointed out above, compression of the spring 36 only results when the teeth of the gear 11 and the pinion 27 meet in end-to-end engagement. To prevent the pinion and gear from remaining in this relative position, I provide means which operates when the spring 36 is compressed and which produces partial rotation of the pin-

ion 27 to permit it to move forward into intermeshing engagement with the gear 11. The means I employ in accomplishing this result is illustrated in Fig. 3.

5 In the construction shown in Fig. 3, the spring 36 operates between an abutment 60 carried by the rod 35 and a second abutment 61 which is secured to the bell crank 37. Rigid with the abutment 61 I provide a sleeve 62 having a helical slot. The rod 35 extends past the abutment 60 and into the sleeve 62 where it is provided with a cross-pin 63 received in the helical slot in the sleeve. The thrust member 32 is so mounted on the forward end 10 of the rod 35 that it will rotate with such rod although being capable of moving axially therealong. This result is readily accomplished by making the forward end of the rod 35 polygonal in cross-section and providing a correspondingly shaped hole in the member 32.

15 The engaging faces of the thrust member 32 and clutch member 22 are provided with an annular series of ratchet teeth 64 so arranged that rotation of the thrust member 32 will be transmitted to the clutch member 22 and thence to the pinion 27.

20 In the absence of end-to-end engagement of the teeth of the pinion 27 with those of the gear 11, this device operates in the same manner as does that illustrated in Figs. 1 and 2. If, however, the teeth of the pinion 27 meet those of the gear 11 in such a manner as to prevent further forward movement of the 25 pinion 27, continued downward movement of the switch button 20 will result in the compression of the spring 36 and relative longitudinal movement of the sleeve 62 and the rod 35. Movement of the sleeve 62 relative to 30 the rod 35, causes a rotation of such rod owing to the engagement of the pin 63 with the helical slot in the sleeve 62. This rotation of the rod 35 is transmitted through the thrust member 32 and clutch member 22 to the pinion 27, 35 thus moving the teeth of such pinion out of end-to-end engagement with those of the gear and permitting the pinion to move forward 40 into intermeshing engagement with the gear. The helical slot in the sleeve 62 has sufficient 45 length to insure that the pinion 27 will be rotated far enough to accomplish this result.

50 I claim as my invention:—

1. An engine starting device, comprising a helical gear connected to the engine, a starter- 55 motor, a switch therefor, a starter-motor-driven shaft, a helical pinion slidable on said shaft into and out of mesh with said gear, an overrunning clutch connecting said shaft and pinion, a thrust member for moving said 60 pinion axially into partial engagement with said gear, the teeth of said pinion and gear being inclined so that the reaction at their faces when the pinion is driving the gear will tend to move said pinion into complete 65 engagement with said gear, and means oper-

ated by said starter-motor switch and acting on said thrust member to move said pinion into partial engagement with said gear before the circuit of said starter motor is closed.

70 2. An engine starting device as set forth in claim 1 with the addition that said last named thrust-transmitting connection is releasable and means operative, when the starter-motor switch reaches its closed position to energize the starting motor to release said connection to permit said pinion to move axially out of mesh with said gear, said last mentioned means being carried by said thrust member.

75 3. An engine starting device, comprising a helical gear connected to the engine, a starter motor, a starter-motor driven helical pinion axially movable into and out of engagement with said gear, said pinion being driven from said starter motor through an overrunning clutch, means for moving said pinion axially into partial engagement with said gear, and means operative after said pinion and gear have been partially engaged for causing rotation of said starter motor and pinion, the teeth of said gear and pinion being inclined so that the reaction at their faces when the pinion is driving the gear will tend to move said pinion axially into complete engagement with said gear.

80 4. An engine starting device as set forth in claim 3 with the addition that said overrunning clutch is in fixed axial relation to said pinion.

85 5. An engine starting device, comprising a helical gear connected to the engine, a starter motor, a starter-motor driven helical pinion axially movable into and out of engagement with said gear, means for moving said pinion axially into partial engagement with said gear, said pinion-moving means including an operating member and a motion transmitting member for transmitting movement of said operating member to said pinion, a spring connecting said two members, means operative to rotate said pinion when said two members move relatively to each other to strain said spring, and means operative after said pinion and gear have been partially engaged for causing rotation of said starter motor and pinion, the teeth of said gear and pinion being inclined so that the reaction at their faces when the pinion is driving the gear will tend to move said pinion axially into complete engagement with said gear and out of engagement with said motion transmitting member.

90 6. An engine starting device, comprising a helical gear connected to the engine, a starter motor, a starter-motor driven helical pinion axially movable into and out of engagement with said gear, means for moving said pinion axially into partial engagement with said gear, said pinion-moving means including two telescoping parts, a helical groove in 95

one of said parts, a projection on the other of said parts for engaging said groove, a spring acting between said two parts, and tending to prevent relative movement between them, one of said parts being connected to said pinion to produce rotation thereof when said parts move relatively and strain said spring, and means operative after said pinion and gear have been partially engaged for causing rotation of said starter motor and pinion, the teeth of said gear and pinion being inclined so that the reaction at their faces when the pinion is driving the gear will tend to move said pinion axially into complete engagement with said gear and out of engagement with the telescoping part to which it is normally connected.

7. An engine starting device, comprising a gear connected to the engine, a starter motor, a starter-motor driven pinion axially movable into and out of engagement with said gear, means for moving said pinion axially into engagement with said gear, said pinion-moving means including an operating member and a motion transmitting member releasably connecting said operating member to said pinion, a spring connecting said two members, means operative to rotate said pinion when said two members move relatively to each other to strain said spring, means operative after said pinion and gear have been partially engaged for causing rotation of said starter motor and pinion, and means operative upon rotation of said starter motor and pinion for releasing the connection between said pinion and said operating member.

8. An engine starting device, comprising a helical gear connected to the engine, a 40 starter motor, a starter-motor driven helical pinion axially movable into and out of engagement with said gear, means for moving said pinion axially into partial engagement with said gear, said pinion-moving means 45 including an operating member and a motion transmitting member for transmitting movement of said operating member to said pinion, a spring connecting said two members, means operative to rotate said pinion when said two members move relatively to each other to strain said spring, said pinion moving means also including a releasable force-transmitting connection which, after partial engagement of said gear and pinion is effected, is released to permit axial movement of said pinion out of engagement with said gear and also to permit free rotation of said pinion.

9. An engine starting device, comprising a gear connected to the engine, a starter motor, a starter-motor driven pinion axially movable into and out of engagement with said gear, means for moving said pinion axially into engagement with said gear, said pinion-moving means including an operat-

ing member and a motion transmitting member for transmitting movement of said operating member to said pinion, a spring connecting said two members, means operative to rotate said pinion when said two members move relatively to each other to strain said spring, said pinion moving means also including a releasable force-transmitting connection which, after engagement of said gear and pinion is effected, is released to permit axial movement of said pinion out of engagement with said gear and also to permit free rotation of said pinion.

10. In combination, a rotatable gear, a rotatable pinion movable axially into and out of engagement with said gear, and means for moving said pinion axially into engagement with said gear, said means including an operating member and a motion-transmitting member releasably connecting said operating member to said pinion, a spring connecting said two members, and means operative to rotate said pinion when said two members move relatively and strain said spring, said pinion moving means including a tripable latch carried by the motion transmitting member.

11. An engine starting device, comprising a gear connected to the engine, a starter motor, means for operatively connecting said gear and said starter motor, said means including a motor-driven pinion and provisions whereby engagement of said gear and pinion will be completed by operation of said starter-motor after partial engagement of said gear and pinion has been effected and whereby said gear and pinion will be demeshed automatically when the engine becomes self-operative, a member movable to effect partial engagement of said pinion and gear, a releasable latch operatively interconnecting said member and pinion, means for releasing said latch after a partial engagement of said pinion and gear has been effected, a movable operating member, and a yieldable connection for operatively interconnecting said two members.

12. An engine starting device, comprising a gear connected to the engine, a starter motor, means for operatively connecting said gear and said starter motor, said means including a motor-driven pinion and provisions whereby engagement of said gear and pinion will be completed by operation of said starter-motor after partial engagement of said gear and pinion has been effected and whereby said gear and pinion will be demeshed automatically when the engine becomes self-operative, an operating member, an intermediate motion-transmitting member, a yieldable connection between said two members, and a releasable connection between said intermediate member and said pinion.

13. An engine starting device, comprising a gear connected to the engine, a starter mo-

tor, means for operatively connecting said gear and starter motor, said means including a motor driven pinion and provisions whereby engagement of said gear and pinion will be completed by the operation of the starter motor after partial engagement of said gear and pinion has been effected and whereby said gear and pinion will be demeshed automatically when the engine becomes self-operative, an operating member, an intermediate member movable axially of said pinion, said intermediate member being connected to said operating member to be moved thereby and having a push connection with said pinion whereby said intermediate member can be operated to push said pinion into partial engagement with said gear and can remain axially stationary when said pinion moves into complete engagement with said gear and releasable means operative when said pinion is out of mesh with said gear for tending to prevent movement of said pinion toward said gear and which last mentioned means includes a spring finger engageable in an annular groove associated with said pinion.

In witness whereof, I have hereunto set my hand at Indianapolis, Indiana, this 3rd day of May, A. D. one thousand nine hundred and twenty seven.

30 WILLIAM CARLETON STARKEY.
